UNITED STATES PATENT OFFICE.

CHARLES A. SMITH AND KENNETH E. BERRY, OF LOCKPORT, NEW YORK.

BOX CONSTRUCTION.

Application filed June 13, 1927. Serial No. 198,522.

This invention relates to a box construction, and has for its primary object the provision of a construction whereby the box will have greater strength and rigidity and

5 the parts so arranged and interconnected that spreading of the side walls is positively prevented.

An object of the invention is the designing of a box in such a manner that the bottom 10 and top may be readily pressed into place and effectively secured in such position by the simple operation of bending certain fasteners into interlocking engagement with companion members on the body of the box.

15 Another object of the invention is the novel construction of fastener which is so designed and arranged that the forcing of the cover or bottom into place is facilitated and in such a manner that the extent of 20 movement of the cover or bottom is limited to assure a flush, neat appearance of the parts comprising the box.

Besides the above, our invention is distinguished in the novel form of fastener 25 that can be easily moved into locking or unlocking position and when in locking position effectively and rigidly securing the parts together.

A feature of the invention is the novel 30 manner of arranging the strips as illustrated so as to perform the dual function of a reinforcement for the sides and a bearing surface for the fasteners to facilitate the locking and unlocking operations.

35 With these and other objects in view, our invention will be better understood from a description of the accompanying drawings, wherein:—

Figure 1 is a perspective view of a box 40 constructed in accordance with our invention;

Figure 2 is a detail sectional view showing the parts separated;

Figure 3 is a view similar to Figure 2 45 with the parts assembled;

Figure 4 is a cross sectional view;

Figure 5 is a longitudinal sectional view.

Again referring to the drawings illustrating one of the many constructions of my invention, the numeral 1 designates the side walls, each consisting of the board sections 2 and securing strips 3. Particular attention is called to the fact that the upper clip 3 and the lower clip 3 are arranged with 50 one longitudinal edge in flush arrangement with the associated ends of the sections 2.

As the top 4 and bottom 5 are of identical construction, the following description will be limited to the top construction so as to prevent repetition. 60

The top 4 is also constructed from a plurality of wood sections 6 secured together by the transversely arranged cleats 7, certain of which are also arranged flush with the associated ends of the sections 6. Particular attention is called to the fact that the area of the top is such as to allow the top to be snugly received within the space defined by the side walls, which not only provides a neater structure but the cover reinforces the 70 side walls against strain. To facilitate this latter effect, a band 8 of wire or other material is passed entirely around the side walls and secured at spaced intervals by staples 9 to the cleats 3. The upper and lower 75 bands are provided at spaced points with loops 10 that extend outwardly from the cleats to provide the openings 11.

Secured to the top are a plurality of wires 12 that have end portions bent back upon 80 themselves to provide hooks 13. These hooks 13 in their initial shape are straight and the portions 14 of the wires which are located at the juncture of the hooks therewith have abutting engagement with the 85 edges of the cleats 3 and the shanks 15 of the hooks are projected through the openings 11 and are bent back into interlocking engagement with the associated loops, as indicated at 16. Thus it will be appreciated 90 that in the insertion of the cover into the box, the abutting engagement of the portions 14 of the wires 12 with the cleats will arrange the cover in a substantially flush position with the upper edges of the walls 95 of the box and upon bending of the hooks about the loops the cover is effectively held in position. It will also be appreciated that with very little effort the hooks can be bent back to their initial position for allowing 100 the cover to be removed.

We wish to call particular attention to the fact that the novel arrangement and shape of the various parts are such that those strains tending to mutilate the box 105 or to cause the release of the cover or bottom are effectively resisted but in a manner that by a very simple operation the various parts may be disconnected.

It is, of course, to be understood that the 110 various parts of the box may be formed of any material found advisable and the fas-

teners may be connected in various other manners than illustrated and associated in other relations and, therefore, we do not desire to be limited in any manner except 5 as set forth in the accompanying claims.

We claim:—

1. A box construction of the class described comprising a side wall structure, a top, a binding element extending about the 10 side wall structure at the upper portion thereof and provided with outstanding loops, a locking element extending across said top and secured thereto and having portions initially extending downwardly opposite an 15 edge of the said top and engageable through respective ones of the loops in the applied position of the top, the locking element being pliable whereby the said portions thereof may be bent back upon themselves into 20 hooked locking engagement with the respective loops.

2. A box construction of the class described comprising a side wall structure, a top, a binding element extending about the 25 side wall structure at the upper portion thereof and provided with outstanding loops, and a locking element extending across said top and secured thereto and having end portions initially extending downwardly opposite 30 respective edges of said top and engageable through respective ones of the loops in the applied position of the top, the locking element being pliable whereby the said portions thereof may be bent back upon themselves into 35 hooked locking engagement with the respective loops.

3. A box construction of the class described comprising a side wall structure, a top to be fitted into the upper end of the 40 side wall structure to close the same, a binding element extending about the side wall structure at the upper portion thereof and provided with outstanding loops at opposite 45 sides of the structure, and a locking wire extending across said top and secured there-

to and having portions initially extending downwardly opposite and spaced with respect to opposite edges of the said top and engageable through respective ones of the loops in the applied position of the top, the 50 said end portions of the wire being bent back upon themselves and the said wire being pliable to provide for the two strand ends to be bent upwardly, after engagement through respective ones of the loops, and in 55 hooked locking engagement with the said respective loops.

4. A box construction of the class described comprising a side wall structure, a top to be fitted into the structure to close the 60 upper end thereof, cleats secured to the outer side of the walls of the side wall structure and extending along the upper edge portion thereof, a binding element extending about the cleats and secured thereto and provided with 65 outstanding loops spaced from an intermediate portion of the respective cleats, and a locking element secured to the upper side of said top and extending across the same and having end portions projecting initially 70 downwardly therefrom substantially at right angles thereto and spaced, at their juncture, with the length of the locking element with respect to the adjacent edges of the said top, whereby to provide for the extension of the 75 end portions of the locking element over the upper edges of the respective walls of the wall structure and the extension of the downwardly extending end portions of the locking member downwardly beside the respective cleats and through said loops, the 80 locking element being pliable whereby the end portions of the locking element over the upper edges of the respective walls of the wall structure and the extension of the downwardly extending end portions of the locking member downwardly beside the respective cleats and through said loops, the locking element being pliable whereby the 85 respective loops.

In testimony whereof we affix our signatures.

CHARLES A. SMITH.
KENNETH E. BERRY.
